UNITED STATES PATENT OFFICE

DAVID P. ANDERSON, OF PITTSBURGH, PENNSYLVANIA

LIFTING MECHANISM

Application filed September 21, 1931. Serial No. 564,181.

This is an invention for a lifting mechanism adapted to operate furnace doors, valves, blast furnace bells and the like. The inventor intends to provide a mechanism which is simple and sturdy, no gears, brakes nor limit switches being necessary.

Having reference to the accompanying drawings:

Figure 1 is a side elevation of an example 10 of the invention arranged to operate a regenerative furnace door.

Figure 2 is a top plan of Figure 1.

Figure 3 is an end elevation of Figure 1.

Figure 4 is a cross-section on the line 15 IV-IV of Figure 1.

In detail the above show a regenerative furnace door 1 raised and lowered by means of a chain 2 passing over a pulley 3, a lifting mechanism constructed according to the present invention being connected to this chain.

This mechanism comprises a pair of differently sized sheaves 4 and 5 commonly mounted on the armature shaft 6 of an electric motor 7 with an endless cable 8 arranged from one 25 of these sheaves to the other in the manner of a differential pulley, forming a horizontal loop 9 and a vertical loop 10.

A pulley 11, carried by the free end of the horizontal loop 9, has its housing connected 30 to the chain 2, and a second pulley 12 is carried by the free end of the vertical loop 10, this latter pulley having a heavy thick-walled housing 13 which substantially counter-balances the door. A pair of chains 14 pass over pulleys 15 to resiliently interconnect the pulleys 11 and 12 through compression springs 16 carried by draw bolts 17. Preferably this is adjusted so that the compression springs carry part of the weight of the door.

40 Although not shown by the drawings, it is to be assumed that this lifting mechanism is located at the top rear end of a bank of furnaces having a number of doors similar to that shown and that there will be a lifting mechanism for each door. The cable 8 is of a length which permits its vertical loop portion 10 to drop the pulley 12 and housing 13 onto a stop 18, which may be the floor or a shelf arrangement, when the door 1 is in raised 45 position. When this occurs the cable 8 is

slackened so that there is not sufficient friction between it and the sheaves 4 and 5 for driving purpose, whereby a safety stoppage occurs when the operator fails to cut off the motor 7 when the door reaches a fully raised 55 position.

This operation is positive and immediate and works without the aid of delicate limit switches or other fragile parts, such as are usually employed in lifting mechanisms.

60 After this stoppage has occurred the cable 8 will immediately tauten when the motor 7 is cut off, due to the drag of the door 1, so that upon reversal of this motor this door will be lowered. No brakes are needed because the

65 friction of the door and its frame will be sufficient to prevent any overrunning. The chains 14 serve to prevent the door falling or the pulleys 11 and 12 causing damage should the cable 8 break in service. They further serve as a means for adjusting the tension of 70 this cable through the draw bolts 17.

75 While a specific example of the invention has been shown and described in accordance with the patent statutes, it is not intended to limit the scope of the invention exactly thereto, except as defined in the appended claims.

I claim:

1. A lifting mechanism including a pair 80 of interconnected differently sized sheaves, an endless cable arranged from one of said sheaves to the other in two looped portions, means for connecting one of said looped portions to the object to be lifted, and means constructed and arranged to slacken the other of said looped portions when the same has moved to a predetermined position and to tauten the same when at other positions.

85 2. A lifting mechanism including a pair of interconnected differently sized sheaves, an endless cable arranged from one of said sheaves to the other in two looped portions, a pulley carried by the free end of one of said looped portions for connection to the object to be lifted, a weighted pulley carried by the free end of the other of said looped portions this portion being vertically arranged and means for stopping the movement 90 of said last named pulley when said first 95 100

named pulley has moved to a predetermined position.

3. A lifting mechanism comprising a pair of interconnected differently sized sheaves, an endless cable arranged from one of said sheaves to the other in two looped portions, a pulley carried by the free end of one of said looped portions for connection to the object to be lifted, a second pulley weighted to substantially counterbalance said object and carried by the other of said looped portions this portion being vertically arranged, means for interconnecting said pulleys, means for stopping the movement of said last named pulley when said first named pulley has moved to a predetermined position and means for rotating said sheaves.

4. A lifting mechanism comprising a pair of interconnected differently sized sheaves, an endless cable arranged from one of said sheaves to the other in respectively horizontally and vertically looped portions, a pulley carried by the free end of said horizontally looped portion for connection to the object to be lifted, a second pulley carried by said vertically looped portion and weighted to substantially counterbalance said object, chains resiliently connected between said pulleys and arranged substantially parallel to the sides of said looped portions, means for stopping the movement of said second named pulley when said first named pulley has moved to a predetermined position and means for rotating said sheaves.

35 In testimony whereof, I have hereunto set my hand.

DAVID P. ANDERSON.
